CLAIM

The ornamental design for a dual easel support or similar article, as shown and described.

DESCRIPTION

FIG. 1 is a front perspective view of a dual easel support or similar article showing my design;

FIG. 2 is a side elevational view, and

FIG. 3 is a rear elevational view thereof.

The side not shown in FIG. 2 is a mirror image of the side shown.

FIG. 2.

FIG. 3.
